(57) **CLAIM**

The ornamental design for a lawn sprinkler control unit, as shown and described.

DESCRIPTION

FIG. 1 is a left front perspective view of a lawn sprinkler control unit showing my new design;

FIG. 2 is a left side view thereof;

FIG. 3 is a back elevation view thereof;

FIG. 4 is a front elevation view thereof;

FIG. 5 is a right side view thereof;

FIG. 6 is a top plan view thereof;

FIG. 7 is a bottom plan view thereof;

FIG. 8 is a top left front perspective view thereof;

FIG. 9 is a bottom left front perspective view thereof;

FIG. 10 is a top left back perspective view thereof; and,

FIG. 11 is a bottom left back perspective view thereof.

The broken lines in FIG. 1, depicting ends of a lawn hose and the ground that the unit is inserted into, represent environmental elements only and form no part of the claimed design.
